AUTOMATIC AMPLIFICATION CONTROL

Daniel E. Harnett, Tuckahoe, and Harold A. Wheeler, Great Neck, N. Y., assignors to Hazeltine Corporation, a corporation of Delaware

Application October 23, 1937, Serial No. 170,556

4 Claims. (Cl. 178—7.3)

This invention relates to television-receiving systems and, more particularly, to the automatic control of one or more operating characteristics of such systems in accordance with the amplitude characteristics of received signals.

The invention is especially directed to the provision of an improved automatic amplification control system for television receivers.

In accordance with present television practice, 10 a transmitted signal comprises a carrier which is modulated during successive intervals or trace periods by high-frequency and direct (average) components representative of an image being transmitted and of its average background illumination, and is modulated between the trace 15 periods or during retrace intervals by synchronizing components which correspond to initiations of successive lines and frames in the scanning of the image.

20 At the receiver, a beam is so deflected as to scan and illuminate a target in a series of frames of parallel lines. The synchronizing components of the received signal are utilized to control the scanning apparatus of the receiver so as to synchronize its operation with that of similar apparatus utilized at the transmitter in developing the signal. The intensity of the beam is controlled by the light modulation components, thereby to reproduce the image.

30 In certain proposed television systems, the video-frequency modulation caused by the image is so impressed on the carrier that increases in the carrier amplitude correspond to increases in brightness of the image, this being termed positive modulation; the background illumination is transmitted directly, that is, by variation of the average carrier intensity during the trace intervals, directly in accordance with the low-frequency light variations or steady background; 35 and the synchronizing impulses are impressed on the carrier in the opposite sense, ordinarily periodically reducing the carrier to zero. While systems utilizing this type of signal have, in general, given satisfactory results, they have been objectionable in that it has been difficult or impossible heretofore to provide satisfactory automatic amplification control. More particularly, since the average intensity of the carrier is varied in accordance with background light-modulation components, the average intensity cannot be utilized to effect satisfactory automatic amplification control in the conventional manner which requires some controlling effect dependent solely upon the average carrier intensity as determined by the power of the transmitting station, its distance, fading, etc., and independent of the modulation.

40 45 50 55 60 Nor can the amplitude of the synchronizing impulses of such a signal be made readily available for this purpose, as they can in the case of negative modulation where these impulses are trans-

mitted on outward peaks of modulation at a relatively fixed amplitude, since, in positive modulation systems, the synchronizing impulses are ordinarily transmitted on inward peaks of modulation.

5 It is an object of the present invention, therefore, to provide in a television receiver improved means for automatically controlling one or more operating characteristics of the receiver in accordance with an amplitude characteristic of the received modulated-carrier signals and independently of the video-frequency modulation components.

It is a further object of the invention to provide an improved automatic amplification control system for television receivers adapted for the reception of positively modulated television signals including background and high-frequency light-modulation components.

In accordance with the invention, a television 20 receiver adapted for the reception of a television signal carrier positively modulated during trace periods by background and high-frequency light components and unmodulated by light components during retrace periods comprises a carrier 25 frequency signal-translating channel in the receiver including means for rectifying the carrier signal translated by the channel only during retrace periods for developing a control-bias voltage, together with means for utilizing the developed voltage to adjust an operating characteristic of the receiver.

In a preferred embodiment of the invention, the control means comprises a signal repeater having an input circuit adapted to receive the 30 modulated-carrier signal and having an output circuit. A rectifier is coupled to the output circuit and means are provided for developing a periodic wave having impulses occurring during the field retrace periods of the signal and for utilizing this wave to control the repeater so as to prevent rectification of the carrier except during the field retrace periods. The scanning wave generator of the receiver may be used as the source of the periodic impulse wave. The unidirectional voltage developed by the rectifier is utilized to control the amplification in various stages of the system, thereby to maintain the signal output intensity within a relatively narrow range for a wide range of signal-input intensities.

40 45 50 55 60 For a better understanding of the present invention, together with other and further objects thereof, reference is had to the following description taken in connection with the accompanying drawing, and its scope will be pointed out in the appended claims.

In the accompanying drawing, Fig. 1 is a circuit diagram, partially schematic, of a cathode-ray tube television-receiving system including

circuits embodying the present invention; Fig. 2 is a group of curves representing certain operating characteristics of the receiver of Fig. 1; and Fig. 3 is a diagrammatic illustration of a 5 positively modulated television carrier wave, to aid in the understanding of the invention.

Referring now more particularly to the drawing, the system there illustrated comprises a receiver of the superheterodyne type including an 10 antenna and ground system 10-11 connected to a radio-frequency amplifier 12 to which is connected in cascade, in the order named, an oscillator-modulator 13, an intermediate-frequency amplifier 14, a detector 15, a video-frequency 15 amplifier 16, and a cathode-ray signal-reproducing tube 17. A line-frequency generator 18 and a frame-frequency generator 19 are also coupled to the video-frequency amplifier and connected to the scanning elements of the cathode-ray tube 20 in the conventional manner. The stages or units 10-19, inclusive, may all be of conventional well-known construction so that detailed illustrations and descriptions thereof are deemed unnecessary herein.

25 Referring briefly, however, to the operation of the system described above, television signals intercepted by the antenna circuit 10-11 are selected and amplified in the radio-frequency amplifier 12 and supplied to the oscillator-modulator 13, where they are converted to intermediate-frequency signals which, in turn, are selectively amplified in the intermediate-frequency amplifier 14 and delivered to the detector 15. The modulation components of the signal are 30 derived by the detector 15 and are supplied to the video-frequency amplifier 16 wherein they are amplified and from which they are supplied in the usual manner to a brilliancy-control electrode of the cathode-ray tube 17 and to the synchronizing-control elements of the generators 18 and 19. The intensity of the electron beam of the tube 15 is thus modulated or controlled in accordance with the video-frequency voltages impressed upon the control electrode of the 35 tube in the usual manner. Saw-tooth current or voltage-scanning waves are generated in the line- and frame-frequency generators 18 and 19, which are controlled by synchronizing-voltage impulses supplied from the video-frequency amplifier 16 and applied to the scanning elements of the cathode-ray tube 17 to produce electric-scanning fields, thereby to deflect the ray vertically and horizontally so as to trace a rectilinear scanning pattern on the screen of the tube and 40 thereby to reproduce the transmitted picture.

45 Referring now more particularly to the portion of the system of Fig. 1 embodying the present invention, for the purpose of developing a control-bias voltage there is provided an intermediate carrier-frequency signal-translating channel including a repeater 20 and a rectifier 21 as shown. The repeater 20 may comprise a vacuum tube of the pentode type having an input circuit coupled to the intermediate-frequency amplifier through a coupling transformer 22, 24 and an intermediate-frequency by-pass condenser 23. A fixed negative bias is provided for the tube 20 from a suitable source, for example, a battery 25 connected between its cathode 50 and ground. Operating potentials are supplied to the anode and screen of the tube from a suitable source, indicated as +B and +Sc, respectively. The diode rectifier is coupled to the output circuit of the repeater by means of a transformer 21, 29 and is provided with a load circuit

5 comprising a resistor 31 and by-pass condenser 30 having a large time constant. This time constant should be considerably greater than the frame period which may, for example, be $\frac{1}{60}$ second, in which event the time constant may be of the order of $\frac{1}{10}$ second. The negative end of the resistor 31 is connected, by way of a suitable low-pass filter including a series resistor 32 and shunt condenser 33 and conductor 34, to the control electrodes of one or more vacuum tubes included 10 in the amplifier 12, oscillator-modulator 13, and amplifier 14, as shown.

15 The frame-frequency generator 19, as stated above, may be of conventional design and adapted to develop a suitable saw-tooth frame-frequency scanning wave. As is well known, however, such a generator also generally develops at certain points of its circuit a periodic-impulse wave having impulses at the frame frequency, and this wave may be taken from a suitable 20 point in the generator. For the purpose of controlling the amplifier 20 and rectifier 21 to limit rectification of the carrier signal translated thereby to the signal-retrace periods, therefore, an output circuit of the generator 19, in which 25 a frame-frequency periodic-impulse wave is developed, is connected by way of a conductor 28 and the winding 22 to the control grid of the tube 20. It is so connected that the impulse voltage 30 is applied with positive polarity to the grid of the tube 20.

35 The operation and results obtained by the system just described may best be understood by reference to Figs. 2 and 3. The graphs of Fig. 2 represent the operating characteristics of the 35 amplifier 20, the abscissae representing time and the ordinates voltage. The line A represents the fixed negative-grid voltage determined by the battery 25, while the line B represents the resultant grid-bias voltage comprising the fixed 40 bias, line A, with the frame-frequency impulse wave superimposed thereon. The cutoff bias voltage of the tube is indicated at C and it will be noted that the normal grid-bias voltage represented by the portions of graph B between 45 the impulses is below cut-off, while the impulses carry the tube well above cutoff, permitting the translation of signals by the tube 20 to the rectifier 21 during these periods.

50 In Fig. 3 there is illustrated the wave form 50 of the modulation envelope of a television carrier wave of the positively modulated type. The time Y-Y₁ corresponds to, or at least includes, the duration of one of the impulses of line B, Fig. 2.

55 The portions of the wave where the carrier is reduced to zero, certain of which are indicated at L, represent line retrace periods or impulses. The portions between the impulses L correspond to the trace portions of successive lines and are 60 modulated as indicated at M₁, M₂, and M₃ by the high-frequency and background light components, except during the frame retrace periods, one of which is indicated at Y-Y₁, during which 65 periods the amplitude of the wave is independent of light modulation. The frame retrace periods include the line impulses as well as additional broad impulses, as indicated at F, which latter constitute collectively a frame-synchronizing impulse.

70 It is well known that, with the positive type of modulation, such as is impressed on the signal shown in Fig. 3, increases in light intensity are represented by increases in the amplitude of the carrier and the average intensity of the signal is 75

varied in accordance with the low-frequency or direct current background illumination components of the image. Thus, in the particular portion of the wave shown, at one point during the line-trace modulation period represented at M_1 , the amplitude of the carrier is such that it reaches the white level, whereas this does not occur during the modulation periods represented at M_2 and M_3 . Since the average intensity of the carrier is thus varied in accordance with background illumination variations, these carrier variations cannot be used for the purpose of amplification control. Nor, as stated above, are there in this type of wave any synchronizing impulses which could be utilized for the purpose in question, since the signal is reduced to zero during the line retrace or line-synchronizing impulse periods. However, since those portions of the wave occurring during the frame retrace period, indicated at $Y-Y_1$, and between the line retrace periods have substantial amplitude and are not modulated by light components, they afford a measure of the intensity of the carrier wave independent of light modulation which may be utilized automatically to control a characteristic of the receiver, such as its amplification.

In the operation of the present invention, therefore, a part of the modulated-carrier output of the intermediate-frequency amplifier 14 is impressed upon the control grid of the tube 20 by way of the transformer 24, 22. While, as stated above, the battery 25 serves normally to bias this tube below cutoff, as shown in Fig. 2, the impulses of the periodic frame-frequency wave, which are shown in line B of Fig. 2 and each of which occurs during a frame retrace period, are impressed upon the control grid of the amplifier and serve to reduce the bias and unblock the tube during at least part of the duration of the frame retrace periods of the wave. Hence, only those portions of the wave which are independent of light modulation are translated to the rectifier 21 and rectified therein. A control-bias voltage is thus developed across the resistor 31 and condenser 30, which is fairly steady and is proportional to the average intensity of the carrier, independent of light modulation. The filter, comprising the resistor 31 and condenser 30, supplemented by resistor 32 and condenser 33, serves to remove fluctuations from the rectified voltage and the resultant unidirectional-bias voltage is impressed on the control electrodes of one or more of the tubes in the stages 12, 13, and 14 to control the gain of these stages inversely in accordance with variations of the average carrier intensity during the frame retrace periods. Thus, the output-signal intensity of the channel, including the stages 12, 13, and 14, is maintained within a relatively narrow range for a wide range of signal-input intensities. It will be noted that where the expression "wide range of signal-input intensities" is employed herein and in the appended claims, it refers to the intensity variations of the received carrier such as occur during the frame retrace periods, independent of light modulation, and not to the relatively smaller average carrier intensity variations which are caused by variation of the average background illumination.

It will be appreciated that the present invention may be utilized automatically to control various characteristics of a television receiver other than its amplification, for example, its selectivity or its tuning.

Thus, while there has been described what is at present considered to be the preferred embodiment of the invention, it will be apparent to those skilled in the art that various changes and modifications may be made without departing 5 from the invention, and it is, therefore, aimed in the appended claims to cover all such changes and modifications as fall within the true spirit and scope of the invention.

What is claimed is:

1. A television receiver adapted for the reception of a television signal carrier positively modulated during trace periods by background and high-frequency light components and unmodulated by light components during retrace periods comprising, a carrier-frequency signal-translating channel in said receiver including means for rectifying the carrier signal translated by said channel only during retrace periods for developing a control-bias voltage, and means for utilizing said voltage to adjust an operating characteristic of the receiver. 10

2. A television receiver adapted for the reception of a television signal carrier positively modulated during trace periods by background and high-frequency light components and unmodulated by light components during retrace periods comprising, means for developing a periodic wave having impulses occurring during said retrace periods, a carrier-frequency signal-translating channel in said receiver including means for rectifying the signal translated by said channel, means controlled by said impulse wave for preventing rectification of said translated carrier except during said retrace periods, thereby to develop a control-bias voltage, and means for utilizing said bias voltage to adjust an operating characteristic of the receiver. 25

3. A television receiver adapted for the reception of a television signal carrier positively modulated during trace periods by background and high-frequency light components and unmodulated by light components during retrace periods comprising, a carrier-frequency repeater having an output circuit, a rectifier coupled to said output circuit, means for controlling said repeater for preventing translation of a signal carrier thereby except during said retrace periods, and means coupled to said rectifier for utilizing the products of rectification to control an operating 40 characteristic of said receiver. 45

4. A television receiver adapted for the reception of a television signal carrier positively modulated during trace periods by background and high-frequency light components and unmodulated by light components during retrace periods comprising, a carrier-frequency amplifier having an output circuit, a rectifier coupled to said output circuit, a scanning-wave generator for developing periodic impulses during said retrace periods, means for controlling said amplifier including means coupling said generator to said amplifier for preventing translation of a carrier signal by said amplifier except during said retrace periods, and means coupled to said rectifier for utilizing the products of rectification to control an operating characteristic of said receiver. 55 60 65
